CLAIM

The ornamental design for a manual laser toner cartridge splitter, as shown and described.

DESCRIPTION

FIG. 1 is a perspective view of a design for a manual laser toner cartridge splitter;

FIG. 2 is a top view of the design for a manual laser toner cartridge splitter, The bottom view is identical;

FIG. 3 is a front view of the design for a manual laser toner cartridge splitter; and,

FIG. 4 is a side view of the design for a manual laser toner cartridge splitter, The right side view is identical.

The broken line showing of the handle is for illustrative purposes only and forms no part of the claimed design.
